UNITED STATES PATENT OFFICE.

PAUL RICHARD HÄUSSLER, OF PLAUEN, GERMANY.

SHUTTLE FOR EMBROIDERING-MACHINES.

1,399,056.

Specification of Letters Patent.

Patented Dec. 6, 1921.

Application filed February 1, 1916. Serial No. 75,555.

(GRANTED UNDER THE PROVISIONS OF THE ACT OF MARCH 3, 1921, 41 STAT. L., 1313.)

To all whom it may concern:

Be it known that I, PAUL RICHARD HÄUSSLER, a subject of the King of Saxony, and residing at Plauen, in the German Empire, have invented new and useful Improvements in Shuttles for Embroidering-Machines, (for which I have filed application in Germany Jan. 28, 1915,) of which the following is a specification.

10 This invention relates to shuttles for embroidery machines and has for its object to provide for certain improvements in such shuttles. In manufacturing embroidery in embroidery machines having upward of 15 one thousand embroidery needles in juxtaposition, it is preferable to use a longitudinal shuttle capable of supporting a large bobbin or spool. It is the object of my present invention to provide a shuttle of this 20 type which owing to its novel structure allows of reliably securing the bobbin therein and results in an increased output of the machine. A machine equipped with the novel shuttle will be able to produce the most 25 delicate embroidery.

Longitudinal shuttles such as hitherto used for supporting large bobbins are not very well applicable in embroidery machines for producing valuable embroidered fabrics, for instance, very delicate embroidery, since with shuttles of this class and having a lateral cover, an angular thread loop will be formed which is liable to have its thread worn or lacerated within the angular portions. On the other hand, in shuttles having bulged side walls it was necessary to cut away or window a portion of these side walls. Although the lid of the shuttle overroofed the thus windowed portion of the side walls, nevertheless there was not any longer a continuous guiding face for the shuttle, so that in making embroidery it would happen that the fine thread be retained by the obstructions the interrupted surface offered, resulting in a breakage of the thread. In such cases, only shuttles without bulged side walls could be used, hitherto. And in order to obtain a larger space within a shuttle of such a type a makeshift 45 was resorted to consisting in cutting away to some extent the inner faces of the side walls, which additional work, naturally, increased the cost of production of such shuttles and yet permitted only such bobbins to

be introduced into the shuttle which, as regards their diameter, corresponded to the width of the inlet opening of the shuttle, while thicker bobbins containing a larger quantity of thread and, hence, requiring a less frequent renewal, could not at all be placed into the shuttle to such an extent that it was possible to close the cover. If, on the other hand, the shuttle were made larger and wider to allow of placing a thicker bobbin into it and yet closing the cover, a shuttle with too wide a guiding surface would result that does not fit the shuttle races of ordinary dimensions. If now, the shuttle races were made to fit such wider shuttles, this would necessitate embroidery needles of an increased length. Long embroidery needles, however, are accompanied by the drawback that they are less steady in consequence of their length and that the point of the needle owing to the spring action of its free end portion is liable to vibrate and, hence, will not prick exactly in accordance with the pattern but very often beside its proper place, which inaccurate working results in the production of an inferior quality of embroidery and an objectionable operation of the embroidery machine. Moreover, with all the shuttles used before this time in embroidery machines, the further drawback had to be faced that the inserted bobbin could easily fall out again while the needle was being threaded or the thread tensioned, unless the bobbin is held in place by the fingers of the operator or by means of more or less complex machinery, to prevent the bobbin from falling out of the shuttle and simultaneously, to insure a proper position of the bobbin within the shuttle. As a result of the wide inlet opening of the shuttle, the bobbin is liable to get into an undesired position while being placed into the shuttle, or when the thread is being tensioned, and must then be moved toward the rear part of the shuttle interior and held there with the fingers before the cover of the shuttle can be properly closed. Otherwise, the bobbin not occupying its proper position within the shuttle, it will be impossible to bring the cover into place since the latter then bears upon the bobbin. These are defects which cause loss of time and complicate the handling of the shuttle.

It is the object of my present invention to

remove these drawbacks. This object I attain by giving the side wall of the shuttle a bulge over the width of the inlet opening so that an interior shuttle space is obtained 5 which is larger than the inlet opening. The introduction of a large spool or bobbin into the thus enlarged inner space of the shuttle is effected by forcing the bobbin through the contracted inlet opening. Once passed 10 through the contracted entrance, the bobbin within the inner shuttle space, expands to its natural size and is then still able to assume an unrestrained position within the shuttle so that it can move without producing a continual friction. This feature of expanding 15 and assuming an unrestrained position within the shuttle space, is of importance, for otherwise the fresh spool would be pressed together and the drawing off of the thread 20 would be impeded. Simultaneously, the uninterrupted contracted inlet opening serves to retain the middle portion of the loosely lying spool in the proper position so that the latter is entirely prevented from falling out 25 of the shuttle, and the cover can be closed unobstructed by the bobbin, whereupon the threading of the needle may be carried out in any convenient manner. By this invention the practical handling of the shuttle is considerably simplified and rendered more convenient. 30

In the accompanying drawings, I have illustrated an embodiment of my invention by way of example; Figure 1 showing the 35 novel shuttle in a side view with the cover of the shuttle in the open position and a bobbin in the action of being forced through the inlet opening of the shuttle. Fig. 2 is a top view of a filled shuttle. Fig. 3 is a transverse section through the shuttle shown in 40 Fig. 2. In Fig. 4 the novel shuttle is shown with a normal entrance width indicated in full lines and an enlarged entrance space indicated in chain lines. In Figs. 5 and 6 are 45 shown shuttles of the old construction, Fig. 5 illustrating a shuttle with one of its side walls partly cut away or windowed, while in Fig. 6 an old shuttle is shown with an entrance of normal width 8 in full lines and 50 an enlarged entrance width 8^a in chain lines.

Referring to the drawings, 1 designates a large sized bobbin and 2 the inlet opening of the shuttle, which opening may be formed either in the normal manner by a pair of 55 parallel walls 8 indicated in full lines in Fig. 4, or by a pair of symmetrically curved walls with which the shuttle illustrated in Fig. 2 is shown to be provided and which are indicated by chain lines 8^a in Fig. 4; 60 the curved entrance walls affording a wider passage for the bobbin. The inlet opening 2 of the shuttle is inclosed by a pair of continuous guiding surfaces or tracks 4. One of the side walls of the shuttle is provided with 65 a considerable bulge 3 for the accommoda-

tion of the large bobbin 1. The bulged side wall contracts toward the entrance 2 to the normal width of the shuttle race and terminates in a part that is symmetrical, with respect to the longitudinal median plane of 70 the shuttle race, to the opposite side wall of the shuttle which is not provided with a bulge; this part serving as the track of the shuttle. In order to further increase the interior space of the shuttle and to decrease 75 the depth of the latter, the bottom is milled away as shown at 7 in Figs. 1 and 3, or is thinned down to the desired extent by a pressing action. The inlet opening 2 is adapted to be closed by means of an ordinary hinged cover 5 having an extended 80 spring 6. This kind of cover has proved most satisfactory in practical working.

In introducing a large bobbin into the shuttle, the thick middle portion of the bobbin is being slightly pressed together and the bobbin then forced through the lateral entrance walls which are separated a width that is less than the maximum diameter of the bobbin. As soon as the bobbin is in its 90 place within the shuttle in which it is then freely lying, the natural elasticity of the thread body will cause the bobbin to expand to its normal size. Since the thickest portion of the bobbin still projects into the 95 space between the contracted entrance walls of the shuttle, the bobbin is held immovably in the proper position within the shuttle even before the cover is closed.

The thus constructed novel shuttle is capable of holding a considerable quantity of thread and to give the same out without causing trouble by becoming inoperative; thus an economical working of the embroidery machine is insured. 100

Various modifications may be made in the novel shuttle, for instance, the side wall of the shuttle could be provided with a slit along the guiding face of the shuttle whereby the track part of the side wall or the 110 inlet opening of the bobbin would be rendered resilient. The shape of the shuttle might be quite different from the one illustrated by way of example. The shuttle track or guiding face 4 may be provided 115 with slight indentations or impressions in order to reduce the bearing surface of the shuttle. The improvements according to this invention may be provided on the right hand side or on the left hand side, or on both 120 sides of the shuttle, whereby the novel shuttle would be applicable in various types of embroidery machines.

It is not at all requisite to enlarge the entrance 2 of the shuttle in the manner indicated by the chain lines 8^a in Fig. 4, for even those bobbins which are sized in correspondence with the larger shuttle space can be passed through the narrow normal entrance determined by the lines 8 in Fig. 4. 125

One or all of these and other modifications not specifically mentioned, may be made without involving a departure from the scope and the spirit of my invention.

5 What I claim and desire to secure by Letters Patent of the United States, is:

1. A shuttle comprising a shuttle body provided with a continuous guiding face, all portions of which lie in the same plane,
- 10 an inlet opening surrounded by said guiding face, and a bulge in the side wall of the shuttle beneath the guiding face portion of such side wall, said bulge being curved both lengthwise of the shuttle and transversely thereof.
- 15 2. A shuttle comprising a shuttle body provided with guiding faces at opposite

sides of its longitudinal center, said guiding faces being farther apart at the middle portion of the shuttle than toward its ends and 20 being located at opposite sides of an inlet opening the width of which decreases from the transverse central line of the shuttle toward the ends, and a bulge in the side wall of the shuttle beneath the guiding face of 25 the respective side wall.

In testimony whereof I have hereunto affixed my signature this twenty-eighth day of December, 1915.

PAUL RICHARD HÄUSSLER.
